UNITED STATES PATENT OFFICE.

LUCIAN M. FOSTER, OF NORWICH, NEW YORK.

INTERNAL-COMBUSTION ENGINE.

1,091,053.

Specification of Letters Patent. Patented Mar. 24, 1914.

Application filed July 8, 1911. Serial No. 637,505.

To all whom it may concern:

Be it known that I, LUCIAN M. FOSTER, of Norwich, in the county of Chenango, in the State of New York, have invented new 5 and useful Improvements in Internal-Combustion Engines, of which the following, taken in connection with the accompanying drawings, is a full, clear, and exact description.

10 This invention relates to certain improvements in internal combustion engines preferably of the four-cycle motor vehicle type and refers more particularly to certain connections between the piston rod and pitman for imparting rotary motion to the 15 crank shaft of the engine.

The main object is to increase the working power and efficiency of this type of engine or rather to reduce the loss of power 20 caused by compression of the explosive mixture, inefficient cleansing of the cylinder from spent gases and excessive shock or vibration of the engine and support upon which it is mounted. In other words I 25 have sought to obviate the loss of power and inefficiency of this class of engines by establishing a resilient differential leverage connection between the piston rod and pitman by which the power required to 30 press the charge of explosive mixture is given back to the propulsion of the crank shaft.

Another object of this resilient connection is to enable the piston to adjust itself automatically to varying volumes of explosive 35 mixture under compression so that the heavier charges, as, for example, under low speed of the engine will be subjected to greater pressure for producing a higher 40 power of efficiency than a lighter charge, as, for example, under higher speed when the power is increased by the momentum.

A still further object is to provide means 45 separate from the cylinder for guiding the piston axially in its reciprocatory movement against diagonal thrusts resulting from direct connection of the pitman to the piston. The effect, therefore, is greater economy 50 in fuel, less shock or vibration of the engine or vehicle upon which it is mounted, reduced wear upon the piston and cylinder, and increased power efficiency.

Other objects and uses will be brought out in the following description.

55 In the drawings—Figures 1, 2 and 3 are similar longitudinal vertical sectional views

of an internal combustion engine embodying the various features of my invention but showing the piston and connections between it and the pitman in different positions. 60 Fig. 4 is a longitudinal vertical sectional view of a portion of the same engine taken on line 4—4 Fig. 1. Fig. 5 is a transverse sectional view taken on line 5—5 Fig. 4.

The engine illustrated is of the four-cycle 65 type having a cylinder —1— supported upon a suitable base or frame —2— and provided with a suitable inlet —3— and exhaust —4— and spark plug —5—, the inlet for the explosive mixture and exhaust 70 for spent gases being controlled by valves —6— and —7— which are operated in the usual manner for this type of engine, said cylinder being also provided with suitable cooling means as a chamber —8— in which 75 water or other cooling liquid may be circulated in any well known manner.

Movable in the cylinder is a reciprocatory piston —9— having a piston rod —10— connected to a cross head —11— which is 80 guided in ways —12— in the sides of the frame —2— so as to guide the piston in a straight line in its reciprocatory movement, thereby obviating any liability of angular 85 thrust and incidental friction and wear to the piston and cylinder arising therefrom as when the piston is connected directly to the pitman.

The cross head preferably consists of 90 opposite parallel arms spaced some distance apart and united at their inner ends for connection with the piston rod —10—, the intermediate portions of said arms being connected by a cross bar or bearing plate —13— for receiving and supporting one end 95 of a coil spring —14— and also serving as a bearing for a rock arm hereinafter described.

Mounted upon the lower or outer end of the frame —2— is a crank shaft —15— to 100 which is connected one end of a pitman —16—. Journaled upon the opposite or inner end of the pitman is a rocker arm —17— having a curved upper or inner bearing face —18— in rolling contact with the 105 under or outer face of the bearing plate —13—, thereby constituting a variable leverage connection between the cross head and pitman for a purpose hereinafter described.

The rock arm —17— is provided with 110 ears or lugs —19— projecting inwardly or upwardly through an opening —20— in

the plate —13— to which is pivoted at —21— one end of a spring tensioning rod or bolt —22—, the opposite or upper end of said rod or bolt being preferably screw-threaded and provided with an adjustable head or nut —23— engaging the adjacent or upper end of the spring —14— for holding the latter under compression and thereby holding the rock arm —17— in contact 10 with the underside of the plate —13—. The rock arm —17— is therefore spring pressed against the bearing plate —13— and constitutes a variable leverage connection between the cross head and pitman, while the 15 spring —22— constitutes a resilient connection between the cross head and rock arm so that the spring together with the rock arm affords what may be termed a resilient variable leverage connection between the 20 cross head and pitman.

It will be observed that the greater portion of the spring —14— and also the connections between the rock arm —17— and spring are located at one side of the produced axis of the piston and cross head and that the normal point of contact between the rock arm and bearing plate —13— is also some distance to the same side of said axis when the piston is at the extreme limit of its 25 30 35 exhaust stroke for cleansing the cylinder or expelling the spent gases through the exhaust port at which time the spring is under minimum tension as shown in Fig. 1 ready to begin its down stroke for drawing in a maximum charge of the explosive mixture, the spring —14— being of sufficient tension to hold the plate —13— in contact with the rock arm —17— during the suction stroke of the piston so as to cause this stroke of the 40 45 50 55 piston to be substantially equal to double the throw of the crank shaft.

When the piston is at the extreme limit of its exhaust stroke as above described, the spring tensioning rod —22— is substantially parallel with the axis of the piston and the point of contact between the rock arm —17— and bearing plate —13— is substantially coincident with the center of the draw rod and the lug —19— is also substantially parallel 50 with said rod so that the maximum leverage of the connection between the bearing plate —13— and pitman is substantially equal to the distance between the produced axis of the piston and a line drawn from the point 55 of contact and through the center of the draw rod parallel with said axis.

Assuming now that the crank shaft is rotating in the direction indicated by arrow X, the piston will be drawn downwardly 60 from the position shown in Fig. 1 and the inlet valve —6— opened to draw in a charge of the explosive mixture, the spring —14— being sufficiently stiff to effect this result without changing the point of contact between the rock arm —17— and bearing 65

plate —13—. Now, as the crank shaft continues its complete revolution thereby advancing the piston to compress the charge, the resistance to further compression gradually increases until it is sufficient to overcome the tension of the spring —14— at 70 which time the piston will have assumed approximately the position shown in Fig. 2, thereby causing the bearing plate —13— to hold the rock arm —17— against further inward movement while the pitman continues to move through the limit of its inward movement, thereby rocking the arm —17— against the bearing plate —13— and causing the point of contact to shift toward the 80 point of connection of said rock arm with the pitman and causing the point of connection between the rock arm and draw rod —22— to be drawn outwardly and downwardly to increase the tension of the spring. 85 The point of contact between the rock arm —17— and bearing plate —13— therefore constitutes the fulcrum of the rock arm with the power applied at the point of connection with the pitman, while the load of compressing the spring is applied to the outer end of the arm, and by connecting the rock arm —17— to the draw rod —22— at a point above the line of contact between said arm and plate —13—, it is evident that as the 90 arm is rocked from its initial position, the point of connection with the draw bar will be quickly thrown outwardly and downwardly, thereby increasing the distance between said point of connection and fulcrum 95 100 or point of contact between the plate —13— and rock arm and at the same time diminishing the distance between such point of contact and point of application of the power and this will continue until the load 105 equals the power, this condition depending somewhat upon the curvature of the rock arm which determines the compression space between the piston and head of the cylinder. In other words, during the compression of 110 the mixture, the point of contact between the rock arm —17— and bearing plate —13— will gradually shift from its initial position until the power and load applied to the rock arm at opposite sides of the point 115 of contact will balance each other and thereby determine the amount of compression space for the explosive charge ready for firing as shown in Fig. 2. Under these conditions it is evident that the compression 120 stroke of the piston is less than its exhaust stroke or throw of the crank shaft and that the spring is under compression and operates to give back the power stored therein to the crank shaft as soon as the pitman is 125 moved by the dead center.

Now, as the explosive mixture is fired its expansive force instantly drives the piston together with the cross head and bearing plate —13— downwardly with greater 130

power than that of the previously compressed spring tending to oppose such action, thereby further depressing the rock arm —17— and shifting the contact point between 5 said rock arm and contact plate —13— nearer to the point of connection of said rock arm with the pitman and thus additionally compressing the spring —14— but with gradually reducing force until such resistance and power tending to compress the 10 spring is again balanced under which conditions the piston assumes approximately the position shown in Fig. 3 at which time the pitman will have passed some distance beyond its dead center and will be acted upon by the combined forces of the power afforded in the spring and expansive force of the fired mixture, all of which forces will be applied to the rotation of the crank shaft as it continues from its dead center on the compression stroke when the turning force is most effective. As soon as these forces are spent which will occur as the piston reaches the 15 limit of its down-stroke, the spring —14— and rock arm —17— will have returned to 20 their normal positions with the point of contact between the bearing —13— and rock arm substantially coincident with the longitudinal center of the draw bar —22— and 25 spring so that on the upstroke of the piston during which the exhaust valve —17— is 30 opened, the spent gases will be effectively expelled from the cylinder and the piston returned to its initial position as shown in Fig. 35 1, thereby effecting a complete exhaust of all of the vitiated gases ready to take in another charge of unadulterated mixture after which the operation previously described is repeated.

40 It is now clear from the foregoing description that during the compression stroke of the piston, the degree of compression of the spring and compression space will depend somewhat upon the quantity of explosive mixture admitted to the cylinder as 45 controlled by the usual throttle and that in like manner under firing of the explosive mixture, the further degree of compression of the spring will depend somewhat upon 50 the amount of the explosive charge but under all conditions, either under the compression or firing stroke, the force applied to the pitman and crank shaft while practically instantaneous is gradual, thereby relieving the 55 engine and carriage or other support upon which it is mounted from excessive shock or vibration, and while a certain amount of resistance to the action of the crank shaft on the compression stroke is necessarily introduced, a considerable part of 60 this resisting power is given back by the spring in the propulsion of the shaft. Another important advantage, however, is the ability of the engine to provide ample compression space for the compression of the

explosive mixture and at the same time to allow the piston to travel to the extreme inner end of the cylinder for positively expelling all of the spent gases and thereby permitting the inlet of an unadulterated mixture which necessarily gives an increased power efficiency and reliability to the engine. 70

One advantage of having the spring eccentric to the piston is that it brings the connection between the center of the spring and cam —17— at one side of the longitudinal center of the connecting rod —16— when the latter is in a vertical position so that immediately upon the explosion and second compression of the spring, such spring gives back its power to the connecting rod and crank arm just after the connection between the connecting rod and crank arm passes the dead center in the direction of movement of the arrow when this increased power is most needed in driving the crank arm through the succeeding quarter turn. Another advantage is that it enables the spring to be brought wholly outside of the cylinder away 85 from the heat. 90

What I claim is:

1. In an internal combustion engine, a cylinder, a piston, a piston rod and a cross head secured to the rod, a bearing plate on the cross head, a spring bearing against the inner side of the plate, and wholly outside of the cylinder, a bearing member for the opposite end of the spring movable relatively to said plate, a crank shaft and a pitman thereon, a rock arm on the pitman, and connections between said rock arm and bearing member, said rock arm being engaged with the outer side of said plate. 95

2. In an internal combustion engine, a cylinder, a piston, a cross head, connections between the piston and cross head, and wholly outside of the cylinder, a bearing plate on the cross head, a crank shaft and a pitman thereon, and a rock arm on the crank shaft in rolling contact with and spring pressed against said plate. 105 110

3. In an internal combustion engine, a cylinder, a piston, a bearing plate, connections between the piston and bearing plate for reciprocating the latter, a crank shaft and pitman thereon, a rock arm on the pitman in rolling contact with the outer surface of the plate, a rod pivotally connected to the rock arm at a point inside of its line of contact with said plate and provided with a head, and a coil spring external to the cylinder and interposed between said head and plate. 115 120

4. In an internal combustion engine, a cylinder, a piston, a bearing plate, connections between the piston and bearing plate for reciprocating the latter, a crank shaft and pitman thereon, a rock arm on the pitman having a curved bearing face in rolling 125 130

contact with said plate, and resilient means external to the cylinder for holding said plate and rock arm in contact.

5. In an internal combustion engine, a cylinder, a piston, a cross head, connections between the cross head and piston, a bearing plate on the cross head, a coil spring wholly external to the cylinder having one end seated on the plate, a crank shaft having 10 a pitman, a rock arm having a curved face in rolling contact with said plate, an ear on the rock arm extending through an opening in said plate, a rod pivotally connected to said ear, and a head on the rod engaged with 15 the opposite end of the spring.

6. In an internal combustion engine, a cylinder, a piston, a crank-shaft and a pitman thereon, a bearing member connected to the piston, a rock-arm on the pitman in 20 rolling contact with said member, a spring wholly external to the cylinder for maintaining such contact, and means actuated by said rock-arm for increasing the tension of said spring as the point of contact between the rock-arm and bearing member 25 shifts toward the axis of the rock-arm.

7. In an internal combustion engine, a cylinder, a piston, a bearing member, rod connections between the piston and bearing

member, a crank shaft, a pitman on the 30 crank shaft, a rock arm on the pitman having a curved bearing face in rolling contact with the bearing member, a draw rod connected to the rock arm at a point inside of the line of contact between the rock arm 35 and bearing member, a head on the draw rod, and a spring interposed between the head and bearing member external to the cylinder for holding the rock arm in contact with said member. 40

8. In an internal combustion engine, a cylinder, a piston, a bearing plate, connections between the bearing plate and piston, a coil spring wholly outside of the cylinder away from the heat and having one end 45 seated on the plate, a crank shaft having a pitman, a rock arm having a curved face in rolling contact with said plate, a projection on the rock arm extending through an opening in said plate, and connections between 50 said projection and spring.

In witness whereof I have hereunto set my hand on this 29th day of June 1911.

LUCIAN M. FOSTER.
